(57) **CLAIM**

The ornamental design for an electric wrench, as shown and described.

DESCRIPTION

FIG. 1 is a front and top perspective view of an electric wrench, showing our new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front and top perspective view thereof showing an environment of use; and,

FIG. 10 is a rear elevation view thereof showing an environment of use.

The broken lines in the figures illustrate portions of the electric wrench that form no part of the claimed design. The additional broken lines in FIGS. 9 and 10 illustrate an environment of use.
